(57) **CLAIM**

The ornamental design for a nasal spray device as shown and described.

DESCRIPTION

FIG. 1 is a perspective view of a nasal spray device; FIG. 2 is a perspective view of a portion of the nasal spray device;

FIG. 3 is a front view of the nasal spray device;

FIG. 4 is a back view of the nasal spray device;

FIG. 5 is a right side view of the nasal spray device;

FIG. 6 is a left side view of the nasal spray device;

FIG. 7 is a top view of the nasal spray device; and,

FIG. 8 is a bottom view of the nasal spray device.

The broken lines shown illustrate portions of the nasal spray device and form no part of the claimed design.

1 Claim, 7 Drawing Sheets
